UNITED STATES PATENT OFFICE.

SIMON P. SLEPY OF WILKESBARRE, PENNSYLVANIA.

IMPROVEMENT IN SEWING-MACHINES.

Specification forming part of Letters Patent No. 90,130, dated May 18, 1869.

To all whom it may concern:

Be it known that I, SIMON P. SLEPY, of Wilkesbarre, in the county of Luzerne in the State of Pennsylvania, have invented certain new and useful Improvements in Sewing-Machines; and I do hereby declare that the following is a full and exact description thereof, reference being had to the accompanying drawings, forming a part of this specification, and to the letters and numbers of reference thereon.

In these drawings, Figure 1 is a side view, and Fig. 2, a front view, in elevation, of the machine with my improvements. The other figures are details of the several parts which will be further referred to and explained, in the course of the description.

In all, like letters and numbers refer to like parts.

The bed plate or table of the machine is designated by the letter A, and the stationary arm by B. On the front or free end of this arm there is a tube (not permanently attached thereto) marked a, capable of only a vertical motion, and otherwise held firmly in position by a groove, nearly inclosing it, made in this end of the arm, or by a plate attached to the arm, or any equivalent means. The object of this tube is to raise, depress, and hold the upper feed-wheels, and consequently these latter are attached to it by means of an arm or axle, b b, in Figs. 1 and 2. This tube is moved by means of the elastic lever c, which passes through an oscillating fulcrum secured in the arm B, and held in any desired position by the ratchet d', which is also attached to the arm B. The outer end of this elastic lever is, of course, attached to the movable tube a.

The feed-wheel d, d is a cylinder revolving upon, but independent of, another and interior cylinder, e, which revolves upon the axle or arm b. The relationship of these parts to each other may be clearly seen in the sectional view, Fig. 3. These two concentric cylinders are moved by clutches attached to rods passing up through, and moved by an arm from the upper end of the needle-bar. The clutches are independent of each other in their operations, one moving the outer cylinder or feed-wheel, the other the inner cylinder, whose function will be explained hereafter. They operate in grooves

upon the cylinders or some other proper arrangement for keeping them from lateral motion on the cylinders. The clutch f, which is attached to the rod f', moves in the groove d'', as seen in Fig. 3. The clutch g, which is attached to the rod g', moves in the groove e', (seen also in Fig. 3,) near the outer end of the inner cylinder e. To each of these clutches there is a band extending around about one-half the cylinder, connecting thereto near one end by a pivot, the clutches being held in close apposition to the cylinders by means of a coiled or other spring, h and h', forming an attachment to the band near their other ends, f'' being the band connected with the clutch f, and the spring h connecting them, g'' being the band connected with the clutch g, and h' its spring. In Fig. 1 the parts f, f', and f'' are shown as they would be when the feed-wheel d operates in a direction opposite to the lower feed apparatus or dog 17, to make the stitches delineated by Nos. 12, 13, 14, 15, 16, 17, 18, 19, and 20 of Sheet 2, or those which show themselves only on one surface. The object of this reversal in the drawing is to show more distinctly the connection between the clutch f and the band f''. In Figs. 4 and 5 these parts are shown in their proper position for acting as a direct feed apparatus. The upper end of each rod, which, as before stated, passes through the arm b, extending from the upper part of the needle-bar, has a screw cut upon it, upon which are two nuts, one above and the other below the arm. The object of these screw-nut is to act as tappets to regulate the throw or movement of the cylinders d and e. The cylinder d, acting as a feed-wheel, has the extent of its motion, and consequently the length of the stitch, controlled and determined by the length of the interval between the two screw-nuts on the upper end of its rod f'.

The object of the inner cylinder e is to give lateral reciprocating motion to the feed-wheel d, by which what is known as the "cat," gloyers' or button-hole, stitch may be made. In Fig. 3, it will be seen that a tongue, d', on the feed-wheel d, projects into a groove on the periphery of the inner cylinder e. The object of this arrangement is to hold the two cylinders together in the lateral reciprocating motion we are about describing. It must be under-

stood, however, that this connection does not prevent the cylinder *d* from having its own independent rotary motion. The cylinder *e* has each of its ends corrugated, as shown in Fig. 6. *i* is a screw passing through the tube *a*, and *i'*, another screw, passing through the cap *j*. (See Figs. 1 and 3.) These screws are so adjusted as to enter the depressions in the corrugated ends of the inner cylinder *e*, and consequently as this cylinder revolves, the elevation of the corrugations coming in contact with the end of the screws, the cylinder is thrown from side to side and thus gives a lateral motion to the feed-wheel and feed, from which necessarily result the stitches just described. The cap *j* can be secured in its place by means of the screw *j'*, and the screws *i* and *i'* are, of course, only to be used in the manner stated when the stitches above referred to are to be made. When these screws are withdrawn or taken out, so as not to act upon the inner cylinder, the whole arrangement that we have been describing acts simply as an upper feed-wheel.

In the further description of my improvements it will be seen that I have provided for another or lower feed apparatus, and, as the two act in harmony with each other, I have arranged the upper so that it may be entirely removed, leaving the whole of the feed action to be performed by the lower feed arrangement. In that case an ordinary presser-foot may be used, as seen at *K*, Fig. 1.

The needle-bar *C* passes through the tube *a*, carrying the arm *l*—heretofore referred to as giving motion to the rods *f'* and *g'*.

The needle may, and I think can, be most advantageously secured in its place by means of the conical screw shown in Fig. 7, and in place at *m*, Fig. 3.

To bring the lower portion of the needle-bar close to the outer cylinder or feed-wheel *d*, the lower portion of the tube *a* is cut out, as seen in Figs. 1 and 3. This, however, will not be necessary when the tube *a*, being made of some thin sheet metal, closely embraces, throughout its whole length, the needle-bar, for then the feed-wheel will be sufficiently near the needle for practical purposes.

Fig. 8 is an apparatus used in sewing when the stitches are to be shown only on one side of the cloth. It is seen in place on the bed-plate, at Fig. 8', turned back and away from the needle. When in use it is of course turned forward as near the needle as may be required. Its uses will be hereafter described. It is held in the desired position on the bed-plate by means of a thumb-screw passing through the slot seen in Fig. 8.

Fig. 9 is a thin strip of metal, or other appropriate material, which I call the separating-plate, having a notch near one end for the needle to play through, and an arm projecting from the other end, which is slotted. This separating-plate can also be attached to the bed-plate by means of a thumb-screw passing through this slot into the bed-plate. Fig. 9 is a

plan view of this separating-plate detached from the bed-plate. The function of this plate is to separate the two folds or pieces of cloth, in ruffling or plaiting, so as to allow the upper one to be moved by the upper and the lower one by the lower feed apparatus, thereby producing the effects or different modes of ruffling shown in 21, 22, 23, 24, and 25, on Sheet 2. It is passed in between the two folds or pieces of cloth until the edge within the notch reaches as near as possible to the needle, without interfering with its free motion.

In the position transverse to the plane of motion of the fabric, and completely separating the upper from any interference with the action of the lower feed apparatus, and vice versa, it is firmly secured in place by its thumb-screw.

Below the bed-plate are other and important portions of my invention, which I will proceed to describe, using numbers instead of letters to designate the various parts.

No. 1 is a slotted block, cast upon or otherwise attached to the lower side of the bed-plate, to support the main shaft, which passes through it, and for other purposes. It is seen in place in Fig. 2, and in part in section in Fig. 10, which figure is a vertical section of certain portions of the machine, to be herein-after described.

No. 2 is the main shaft, scarcely visible in Fig. 2, but a portion is seen in section in Fig. 10.

This main shaft extends from the driving-wheel 3, through the two cheeks of the block 1, and has upon it, between these cheeks, the adjusting-sleeve 4.

It thence passes through a cog-wheel, No. 5, secured upon it, (seen in dotted lines in Fig. 11, and in section in Fig. 10,) and thence through a compound cam, 6 and 6'. (Seen in place in Fig. 2, in section in Fig. 10, and end views in Figs. 11 and 12.) This compound cam plays loosely upon the main shaft, and is moved, as will hereafter be seen, by a system of cog-gearing shown in Fig. 11.

The main shaft then passes and is firmly attached to and terminates in another compound cam, 7. (Seen in place in Fig. 2, in section in Fig. 10, and separately in Figs. 13, 14, and 15.)

The driving-wheel 3 may be firmly attached to the main shaft 2, but I prefer having it loose, in which case a limited extent of motion may be given it to the extent allowed by the pins 8, 8, between which the key 9, Fig. 16, in the end of the shaft, plays.

The object of this play in the main shaft will be explained when describing the double-hooked spreader 10, attached to the face of the compound cam 7 on the outer or right-hand face of the driving-wheel.

As we look at the drawing, Fig. 2, there is attached one end of the link 11, (see Figs. 1, 2, and 16,) which moves the needle-lever 12, shown in Figs. 1 and 2. This link I prefer

making of steel, longitudinally corrugated, to secure the combination of lightness, stiffness, and strength.

The block 1 has its lower portion divided into two legs or cheeks, to one of which, and I prefer the outer or right-hand one, as seen in Fig. 2, is attached a link, 13, by an oscillating screw, 14, the other end of the link being attached to an arm of the feed-dog 17.

The lower portion of the inner leg or cheek 1 receives the end of the screw 15, which supports and forms the axis of motion of the looper-lever 16, and adjusts its position.

4 is a loose sleeve upon the main shaft, to which it can be firmly affixed, when necessary, by means of the set-screw shown on its face in Fig. 2, and in section at Fig. 10.

The toothed wheel 5 operates the compound cam 6 6' by means of a pinion, 5', as seen in Fig. 11. This pinion turns upon a shaft or axis attached to the inner or left cheek of the block 1. The gearing is so arranged as to cause one revolution of the compound cam 6 6' to two of the main shaft. That part of this compound cam marked 6 is of an oval or ovoid form, as shown in Figs. 11 and 12.

Sunken into its face is an excavation, surrounded by inverted cogs, which take into the cogs of the pinion 5', and through which it receives its motion upon and around the main shaft.

Upon the periphery of the portion 6 of this compound cam there is a double-curved flange, 6", to give motion to the feed bar or dog 17.

It should be observed, also, that the oval or ovoid form of this part of this compound cam, acting upon the pin or friction-roller 17, attached to the under surface of the feed-dog 17, alternately lifts up and lets fall the latter, and thus causes it to take hold and let go the feed or cloth.

In the drawings of this part 6 of the compound cam 6 6', as shown on Figs. 11 and 12, I have given the oval or ovoid an exaggerated ellipticity.

The difference in the length of its longer and shorter axis will be determined by the vertical play or vibrations required to be given to that end of the feed-dog 17 which seizes the feed or cloth, so as to insure its proper advance to the needle, and then drop from and entirely relinquish it until it makes a new seizure and advance.

This vertical motion may not generally be more than a sixteenth, an eighth, or a quarter of an inch, and consequently the difference in the length of the axis of the ovoid need not be greater than these measures, to enable it to perform the required function. I have, therefore, exaggerated the ellipticity of this part in the drawings, to cause its construction and purpose to be more readily appreciated.

The other portion, 6', of this compound cam is circular in its outline, as seen in Fig. 12; but as the main shaft 2 does not pass exactly through its center, but nearer one side than

the other, it becomes an eccentric or cam in its action.

The object of this arrangement is to operate upon the arms 17" attached to the feed-dog 17, for the purpose of giving a transverse reciprocating motion to the latter.

There are adjusting-screws, as seen in the drawings, near the lower end of these arms, by the adjustment of which the lateral throw of the feed-dog or bar may be increased or diminished.

The screw 17", passing through the upper part of the arm 17", or otherwise attached to the feed-dog, is intended to operate upon the side of the flange 6", opposite the friction-roller or pin 17, so as to insure the proper reciprocating motion to the feed-dog, and, by adjustment, give the required length of stitch.

The next part that presents itself, looking at the machine as shown in Fig. 2, and detailing the parts as there represented from right to left, as we have done above, is another compound cam, 7.

As before stated, the main shaft is permanently attached to this cam; consequently they both make the same number of revolutions in the same time, differing, therefore, in this respect, from the compound cam 6 6' just described.

This compound cam 7 is represented apart from everything else, and as if seen in full view from the right in Fig. 15, and with other parts hereafter to be described in Figs. 13 and 14.

This cam is, in fact, two cams of different forms, permanently attached to each other; the one on the right being of an ovoid form, or, perhaps, more properly speaking, of a compound figure, represented by a semicircle, and a more or less exact parabolic curve, with an acuminate apex. Its form is best seen in the unshaded parts of Figs. 13, 14, and 15. Its purpose is to act upon the upper end of the curved looper-bar 16, and thus throw the looper-needle back from contact with the descending needle. Its acuminate point may be seen in the very act of performing this function, through the notch in 10 in Fig. 1.

The other portion of this compound cam 7 is best represented by Fig. 15, which is the form I prefer, though other forms are represented in Figs. 13 and 14. In the former, Fig. 15, it will be seen that the outlines of this part of the cam are made up of the arcs of two circles of different radii. One of these arcs is about two-thirds of an entire circle, and strikes the acuminate point of the other division of this compound cam at a tangent at or near the center of the arc.

The other arc is much flatter, having a much larger radius than the former, and becoming confounded for a short distance with the circular portion of the ovoid cam already described.

The object or function of this division of this compound cam is to act upon the short

arm of the looper-lever 16, throwing the looper-needle forward to and beyond the ascending needle, and holding it there until the acuminate point of the other division of this cam begins to act, and throw the looper-needle back out of the way of the descending needle.

The front face, looking at Fig. 2 from the left, of this compound cam 7 is excavated, as seen in section in Fig. 10. The excavation is made to receive the spherical bobbin-case 18, as seen in Fig. 2, and in section in Fig. 10, or the spool-case shown in section in Figs. 17 and 18, and in place at 19, Fig. 1.

Above and extending about half around this excavation, attached to the face of the compound cam 7, there is a projection, 10, which I call a double-hooked spreader. (Seen in front view in Fig. 1, in side view in Fig. 2, in section in Fig. 10, and partially in Figs. 13 and 14.)

This spreader is very distinctly seen in Fig. 1 at the moment one of the hooks is about to catch the loop from the needle, the needle then being at its greatest depression.

As soon as it (the needle) begins to ascend it begins to form the loop, and as it moves very near the face of the spreader 10', as the loop forms it spreads out into the notch 10'', formed by the hooks, and as the spreader revolves with the cam 7, to which it is attached, it brings the point of one of the hooks into the loop, and thus secures it, and then continuing its revolution it brings this loop over the sloping back of the spreader, and carries it thus under and around the spherical bobbin, or spool-case, when it is thrown off, to be taken up.

Projecting from the lower edge of this spreader is a lip, 20, extending beyond the vertical axis of the spherical bobbin-case or spool-case, as seen in front view, Fig. 1; side view, Fig. 2; and in section, Fig. 10.

A slot is cut in this lip, at or near its junction with the spreader, to allow the needle to descend through it.

The object of the lip 20, itself, is to throw the thread from the bobbin in the spherical case, or the spool in the spool-case away from and so as not to come in contact with the hooks of the spreader, as seen in Figs. 2 and 10, and also to secure more effectually the throwing of the loop from the needle around these cases, and thus preventing it from again coming in contact with the hooks of the spreader 10.

The looper-lever 16 is a curved lever, working on the neck of the screw 15 as fulcrum. (See Figs. 1 and 2.)

This screw is attached to the lower end of the cheek of block 1, as shown in Fig. 1, and not only serves as a fulcrum, but also as a means of throwing the looper-needle in or out of action, and adjusting it for use.

The short arm of this lever is operated by

that division of the cam 7 which I have described as having a periphery formed by two arcs of circles of different radii.

The long arm of the lever 16, curving up around the compound cam 7, has its extremity divided into two branches, one of which extends over toward and is acted upon by the acuminate point of the ovoid division of cam 7, and the other branch serves to carry the looper-needle.

This lever is seen very distinctly as 16 in Fig. 1, and 16' being the short arm, 16'' the division of the long arm, operated upon by the acuminate points of cam 7, and 16''' the division carrying the looper-needle.

The spherical bobbin-case, and spool-case, as shown in position in Figs. 1 and 2, (18 and 19,) are held there by the clamp 21, but not pressed upon by it so closely as to prevent the thread of the loop from passing easily between it and them.

The form and arrangement of the clamp 21 may be seen in the above Figs. 1 and 2. It is held, it will be seen, to the lower face of the bed-plate A by a thumb-screw, 22, by which it may be firmly fixed in its proper position.

The spherical bobbin-case is hollow, and divided into two hemispheres, united by a male and female screw, along a horizontal or equatorial line, as seen at 18 in Fig. 2.

In Fig. 10 there is shown a vertical section at 18, through the sphere, displaying the screws and the bobbin 23 in place.

To hold the bobbin in its proper place, a notch is made on each side of the lip of the lower hemisphere, so that when the upper hemisphere is screwed down it holds the points of the bobbin therein, but not so tightly as to interfere with its rotating freely on these points.

The thread from the bobbin passes under a tension-spring, 24, and thence out through an orifice in the upper part of the sphere, between the looping spreader 10 and the lip 20, and thence under the latter, so as to be thrown to a distance sufficient from the hooks of the spreader to prevent it from coming in contact therewith.

Figs. 17 and 18 are vertical sections of the spool-holder, seen in position at 19, Fig. 2. These sections show two modes of applying tension to the thread, as it passes from the spool.

In Fig. 18 the thread passes under the spool, and up through the center thereof, by the side of or through the pole upon which the spool turns.

A tension plate or disk, acting upon the thread, is seen in the bottom of this section, supported by a bowed spring, which is regulated in its pressure by a screw.

Fig. 17 shows another form of applying tension, which I prefer. In this arrangement the thread passes from the spool under a curved spring, 25, secured at one end, and nearly op-

posite thereto, to the inner side of the case by two pivots, the other end free, passing nearly or quite around the inside of the case.

The pressure of this spring upon the thread increases with its approach to horizontality, assuming the case to be standing upright or vertical. Its free end, therefore, can be moved up or down, farther or nearer to this position, by a common needle or pin passed through the slot 26 made in the side of the case for this purpose.

After passing under this tension-spring, the thread issues from an orifice at the side of the case, near the top, and is controlled in its ascent by the lip 20, as in spherical case.

I have described the long arm of the curved lever 16 as being divided into two branches, to one of which is attached the looper-needle. The arrangement for this attachment is shown in Figs. 1 and 2, but detached, and more distinctly in Fig. 14, in which 16" is the arm.

On the extremity of this arm there is affixed a screw, carrying a plate between it and the end of the arm, and between these two (the screw-head and the plate) the looper-needle is carried, by being compressed between the two.

In Figs. 19, 20, and 21, I have shown a part of the lever-arm, together with the plate, screw-head, and the needle, the latter in several of the positions it may assume in the performance of its functions.

The plate 27 has a long notch on its side, on one edge of which the point of a spring, 28, acts, and at the other edge there is a stop-pin, to prevent the spring from carrying the plate and screw, and, consequently, the needle, beyond a certain range of motion.

To secure this motion more perfectly, I find it best to cut a female screw on the plate, as well as the arm, for the reception of the screw 30, it being understood that the screw and plate both oscillate.

The looper-needle 31 may be straight, or slightly curved, and has one end pointed, and with an eye for carrying a thread, and the other end terminating in a fork, with prongs of unequal lengths, sometimes called barbed.

The eye-pointed end is used in all stitches involving the double loop, the forked end in single loop.

The needle in Figs. 14, 19, 20, and 21 is shown as fixed for making the double-loop stitch. To prepare it for a single loop only requires that it should be loosened from the grasp of the screw 30 and plate 27, and reversed, the forked end occupying the place of the eye-point, as shown in the drawings.

I have hereinbefore referred to the link 11, proposing to make it of corrugated steel. This link being connected with the driving-wheel, has its other end loosely attached to, so as to be adjustable upon, the needle-lever 12, which, it will be seen, descends, in an arc, a considerable distance below the bed-plate, and moves upon the fulcrum 32', (in dotted lines,) and

operates the link 12', which forms the connection between it and the needle-bar. I prefer to make this lever 12' also of steel, or steel plate, corrugated or not, as may be deemed best. The connection between the link 11 and lever 12' being made by a stirrup, 11', which moves freely up or down upon the lever 12', a variation in the length of leverage may be made, and a consequent change in the throw of the needle, by securing the clamp 12" at the desired point to accomplish the purpose. But the function I deem most important in this arrangement is to raise the needle entirely up and out of the way, for the admission of the material beneath it, without disturbing any other part of the machine. This is done by raising the link 11 up to or near the bed-plate, and holding it there until the cloth is properly adjusted, when it may be allowed to fall down again to the clamp 12". The curve of the arc of the needle-lever 12', between its lower end and the fulcrum 32', is formed very nearly by a radial line, extending from the center of the main shaft 2 to the center of said fulcrum 32".

On the other or upper limb of the lever 12', represented in dotted lines on Fig. 1, because it is shown out of the position it ought to occupy, is a series of pins on the face thereof, opposite the face of the stationary arm or goose-neck B, upon which there is another series, also dotted, occupying a position intermediate between those on the lever-arm. These pins having the upper needle-thread passing among them, as indicated, act as a take-up arrangement.

When speaking, in the previous part of this description, of the driving-wheel 3, I stated it might be firmly attached to the main shaft 2, or allowed a limited range of motion, controlled by the pins 8 and key 9, the object of which motion was to be explained when describing the double-hooked spreader 10, attached to the face of the compound cam 7. Having inadvertently omitted to give this description at that place, I will now proceed to do it.

In describing the operation of the spreader 10 it was stated that the hooks thereon were intended to enter and catch the loop from the needle as it fell into the notch 10", between these hooks.

Under some circumstances it may happen that the needle may not have risen high enough before the arrival of the hook to form a loop large enough for the point of the latter to insinuate itself therein. To prevent this occurrence, it may be necessary sometimes to retard slightly the advance of the hook, that time may be given for the development of the loop. This I accomplish by allowing the main shaft to rotate on its axis on the driving-wheel to the limited extent of the distance between the pins 8, between which the key 9 moves.

As the compound cam 7, to which the spreader 10 is affixed firmly, is firmly attached to the main shaft, this retardation of its motion, which must occur to it, from well known physical

laws, will be communicated through the cam 7 to the spreader and its hook, retarding the approach of the hook to the needle long enough to allow the latter to form a loop of a proper size to be caught upon the hook.

When all the parts of my machine are properly constructed, and due attention given to keeping as well as putting them in true adjustment, the occurrence of the irregularity of its action, for which this provision is made, is not likely to take place, even when the main shaft is permanently attached to the driving-wheel. As it may, however, under some circumstances, I have deemed it necessary to devise a plan of meeting and providing for it.

I will also avail myself of this occasion to explain, more fully than has heretofore been done, the function of the sleeve 4 and its set-screw.

My machine is capable of making a stitch with one, two, or three threads, these being severally the needle-thread, the looper-thread, and the spherical or spool-case thread.

In all these stitches the needle-thread is necessarily involved, the combinations being with one or both of the others.

When this combination is between the needle-thread and the eyed looper-thread, making what is commonly called the double-loop stitch, the spherical or bobbin case thread is not involved, and consequently it will then be necessary to have the machine so adjusted that the double-hooked spreader 10 shall be in such a position that it cannot catch the loop formed by the needle-thread, as it would do, its revolutions being continual, if it occupied the position it must do when the spherical-ease or spool-case thread forms an element of the combination. In other words, when the double-loop stitch, in any of its herein-after-mentioned varieties, is alone to be made, the hooked spreader must be so far removed from the needle that the hooks in these revolutions cannot catch the loop formed by the needle.

This is accomplished by giving the main shaft a play upon and in the direction of its axial line. With this play, or capacity for axial movement, the spreader and cam 7 can be moved at will, with the main shaft to which they are attached, as before said, so far to the right, looking at the machine as represented in Fig. 2, that the hooks of the spreader will no longer be near enough to catch into the loop of the needle, until they shall have passed beyond it.

But this axial motion of the main shaft must not be entirely free—that is, it must be controllable; otherwise the spreader-hook might vary its position from light causes, and thus interfere with the certainty of the operation of the machine, in making its several kinds of stitches. It is mainly to prevent this that I use the sleeve 4 and its set-screw.

This screw fits loosely upon the shaft, and closely, but not tightly, between the cheeks of block 1, and the thumb-screw is used to fix it

tightly, when necessary, upon the main shaft, with which it then revolves.

When it is desirable to remove the spreader-hook out of the way of the needle-loop, to prevent its interfering with the stitch to be formed, either by the thread of the needle alone or by the combination of the threads of the needle and looper, it is only necessary to loosen the thumb-screw of the sleeve 4 from its grip upon the shaft, push the latter, carrying with it, of course, the cam 7 and spreader to the right the required distance, and again clamp the sleeve to the main shaft by means of the thumb-screw. This movement can be best made by pressure upon the excavated face of the cam 7.

Another very important function which this sleeve 4 and set-screw performs is in the adjustment of the face of the spreader and the hooks to the needle. By this adjustment the hooks may be brought so nicely up to the needle that the slightest development of its loop will enable the hook to enter and secure it.

On the extreme right of Fig. 2 is shown my improved apparatus for transferring the thread from the spool to the bobbin.

This apparatus is attached to the under side of the bed-plate A by a screw, 32, upon which it turns, and by which it is fixed in position when in action.

The apparatus itself consists of a frame, 33, with two descending arms, 33' and 33'', a large flat driving-wheel, 34, attached by an open movable collar to the frame, a smaller vertical wheel, attached to a spindle passing through the arm 33'', and driven by friction upon the outer edge of the face of the larger wheel.

The spindle on which this smaller wheel is fastened projects through the arm 33'' far enough to receive and hold a spool, 35, which revolves loosely upon it.

Through the other arm, 33', of the frame, another spindle passes, ranging in a line with that through 33'', and fixed in place by a screw, 36.

The interval between the two spindles admits the bobbin 23, Fig. 19, and is held in place by the adjustment of the spindle in 33'.

On the under side of the larger wheel, 34, there is a slide or shift bar, 37, attached, having a hole in its free end, and on the outer side and upper end of the arm 33'' there are arranged a tension-screw and spring, 38.

The thread from the bobbin 23 passes under the tension-spring, which is adjustable to the required tension by its screw; thence to and through the opening in the collar of the wheel 34; thence through the hole in the slide 37, and thence on the bobbin.

I have described the pin for holding the spool as a continuation of the spindle for holding one end of the bobbin, but instead of that this pin may be independent of the spindle, and fixed to the arm 33''. Cog gearing may

be used for driving this apparatus, if preferred.

The object of the slide or shift bar 37 is to regulate the winding of the thread on the bobbin, so that an ordinary bobbin-form can be made, such as would be required for the bobbin or spool-case 19, or a spherical ball, adapted to the spherical case 18. This is done by adjusting the slide 37 to the position required to make one or the other of these forms.

To put this apparatus in action, the whole is turned upon the screw 32 until the edge of the flat wheel 34 comes in firm contact with the outer face of the driving-wheel 3, and there fixed by tightening the screw. The sewing-machine being then put in motion, the winding from the spool to the bobbin goes on, until the proper size is given to the ball or bobbin, without the use of the hand to direct the thread, or any other special attention.

In fact, this apparatus will distribute the thread automatically back and forth upon the spool as regularly, or perhaps more regularly, than it can be done when the movement of the thread is directed by the hand, as is generally, if not always, done in sewing-machines.

In operating my sewing-machine I use one, two, or three threads. One of these is carried by the needle proper; another by the looper or looper-needle, and the other is furnished from the spool in the spool-case 19, or the bobbin in the spherical case 18.

By this combination I make, without the removal therefrom or addition thereto of any machinery not already in my machine, changing the direction of the feed, (see Sheet 2,) first, the single-loop stitch, Diagram 1, in which but one thread—that of the needle—is used; second, the double-loop stitch, Diagram 2, in which the needle-thread and the looper-thread are combined; third, the shuttle-stitch, Diagram 3, in which the needle-thread and the spool or bobbin thread are combined; fourth, the single-loop and spool or bobbin stitch, Diagram 4, in which the needle-thread and spool or bobbin thread are combined, and the forked end of the looper-needle used; and, fifth, the double loop and shuttle stitch, Diagram 5, in which the needle-thread, the looper-thread, and the spool or bobbin thread are all combined.

In these five primary stitches the feed is supposed to act in a direct line, whether the upper or lower feed, or both, are in operation. But as these can be made to operate laterally, by which the cloth will be moved from side to side as it advances, another series of stitches of the same number, which I call zigzag, can be made.

These are designated also on the second sheet of drawings, by Diagram 6, the single-loop, zigzag, or grover stitch; Diagram 7, the double-loop zigzag stitch; Diagram 8, the zigzag shuttle stitch; Diagram 9, zigzag single-loop and shuttle stitch; and Diagram 10, the zigzag double-loop and shuttle stitch.

When these zigzag stitches are made near

the edge of the cloth or other fabric, so that one line of the interlockings shall be just on the outside of that edge, while the other line is, as usual, through the cloth or fabric, I then have a strong and useful binding-stitch, and when a proper aperture has been made through the cloth, and the feed suitably adjusted for the purpose, a very perfect and durable button-hole stitch may be made by the same process—that is, by causing one of the interlockings of the thread or threads to take place as in ordinary sewing, and the other on the edge of the aperture, as in the above binding-stitch.

Thus my machine is capable of making ten varieties of stitches, five direct or in one continuous line, and five zigzag or compound double lines, all passing entirely through the cloth. Besides these, by the assistance of the roller, Fig. 8, it will make ten more stitches of the same kind not passing through the cloth, and therefore showing themselves only on one side of the cloth. These, following the same order of direct and zigzag stitches, are indicated also on Sheet 2, as Diagrams 11, 12, 13, 14, 15, 16, 17, 18, 19, and 20. And, further, by the assistance of the separating-plate, Fig. 9, it will make five varieties of ruffles, by causing the upper feed to move in four of them faster than the lower, and four varieties of plaits by causing the lower feed to move faster than the upper. The five varieties of ruffles are also exhibited on Sheet 2 by Diagrams 21, 22, 23, 24, and 25.

In the preceding portion of this specification the mode of operation of the upper feed apparatus was so fully explained that it is not deemed necessary to refer further to it. I will, therefore, proceed to explain the operation of the lower feed.

As before stated, in describing this part, the feed-dog 17 is connected by a bar to the link 13, and has two arms, 17", only one of which is shown in the drawing, Fig. 1, stretching down on each side of cam 6', one or both arms having a screw passing through it or them, near the lower end.

When the object is to make any one of the direct stitches above described, a screw, 39, on the lower end of the link 13, is screwed up tight on the vibrating screw 14, and the screw or screws in the arm or arms 17" are unscrewed to such an extent that the cam 6' will not touch it or them in its revolutions.

In this condition the feed-dog 17 moves in a direct line back and forth, under the influence of the flange 6", and rises and falls to seize and release the cloth, under the influence of the oval cam 6, to the periphery of which this flange 6" is attached.

The length of the stitch or the throw of the feed-dog 17 can be regulated by the screw 17".

When the zigzag stitches are to be made either alone, by the lower feed, or in conjunction with the upper feed, the screw 39, on the lower end of the link 13, is unscrewed to permit motion in the link, so as to oscillate as

well as vibrate, and the screw or screws in arms 17" are screwed in, until they will be acted upon by the cam 6, and so adjusted as to give such length of vibration horizontally to the feed-dog 17 as may be desired to give the required width to the stitch.

It must be recollect that either the upper or lower feeding devices can be dispensed with when desirable, leaving the feed to be carried on by one remaining in action.

When the lower feed is not wanted to perform its function as a feed apparatus, the screw 17", which is operated upon by the flange 6", and the screw or screws on the arm 17", are withdrawn to the proper distance to prevent their being acted upon, and then the feed-dog 17, with all its attachments, can and is to be pushed toward the driving-wheel, until disengaged from the compound cam 6 6', in which position it will remain entirely quiescent.

In making the stitches represented on Sheet 2, from Diagram 11 to 20, inclusive, in which they show themselves only on one side of the cloth, the roller, Fig. 8, is used.

In these, the action of the two feeds is in opposition to each other—that is, while the lower feed acts in its usual direction, drawing the cloth forward to be sewed, the upper feed acts in an opposite direction to draw it away after it has been sewed.

This is accomplished by taking off the clutches *f* and *g*, and their appendages, and reversing them. This gives the upper feed a direction opposite that of the lower, the roller, Fig. 8, being at the time between the two, the cloth passing up over the roller, and back under the upper feed.

It is not absolutely necessary a roller should be used in this case. A stationary flat bar with a round edge will answer the same purpose.

In making the ruffles represented on Sheet 2, Diagrams 21, 22, 23, 24, and 25, both feeds are used.

The separating-plate, Fig. 9, secured, as before described, to the bed-plate A, Figs. 1 and 2, being placed between the two membranes or fabrics to be operated upon, is pushed close up between the two feed apparatus, so that the feed and needle will have to play in the long notch on its edge.

In Diagram 21 both feeds act in a direct line. In 22 the upper feed acts in a zigzag, while the lower acts direct.

In Diagram 23 both feeds have a slight zigzag effect in opposite directions. In 24 the lower is zigzag or vibratory, the upper feed direct, and in 25 both are zigzag or vibratory.

In Diagrams 21, 22, 24, and 25 the upper cloth is fed faster than the lower. This is accomplished by bringing the screw-tappets on *f*, Fig. 1, nearer together, so that the length of the throw of the upper feed at each stitch will be increased, and this difference may be further increased by lessening the throws of the lower feed.

In Diagram 23 although both feeds act in a zigzag direction, the feed apparatus on both sides have the same throw, but vibrated in alternate opposite directions; but in Diagram 25 the upper feed is again faster than the lower, and both vibrate, but in alternate opposite directions.

In Figs. 19, 20, and 21 I have shown the operation and several positions of the looper-needle in making the double-loop stitch. I do this because my arrangement is different from any other with which I am acquainted.

My looper-needle 31 is pointed at one end, with an eye for carrying the thread in that end, and forked with unequal branches at the other.

In making the double-looped stitch, whether alone or in combination with the lock or shuttle stitch, the eye-point is in advance and carries a thread.

In Fig. 1 the needle is shown as having descended to its utmost extent, while the looper is thrown back by the action of the acuminate point of the ovoid cam 7 upon the arm 16" of the bent lever 16.

In Fig. 19 the point of the needle has ascended nearly to the lower side of the bed-plate and the arm 16" being relieved by the revolution of the cam 7, the looper has come forward in an oblique direction, owing to the position it occupies in its fastenings in arm 16", just behind the ascending eye of the needle, where it enters and engages the loop of the needle; the needle continuing to ascend and the looper to advance, the needle-loop is held thereon until the needle again descends, when it passes behind the looper, as shown in Fig. 20, between its former loop and the thread in the eye of the looper.

When the parts have got to about this position, the looper, beginning again to be withdrawn by the ovoid cam 6, as seen in Fig. 21, is slightly sprung back by coming in contact with the needle, but finally escapes and throws off the needle-loop, which is caught on the looper-thread.

I have described the compound cam 6 6' as being made of two parts, 6 and 6', but united together, and thus forming in fact only one cam. It is not necessary, however, that this union should be made. It is only necessary that the relative revolutions of the two parts, as described, should be maintained, so that this compound cam, united or divided, should only revolve once in making two stitches. And the same observation may be made in relation to the compound cam 7 and the double-hooked spreader 10.

The two parts of this cam 7 may be made separate, and thus produce the same effect as that described, provided they are arranged in relation to each other as shown in the drawings.

Nor is it absolutely necessary that the spreader 10 should be attached to the face of cam 7. By attaching it directly to the end of the shaft, or around an enlargement of the end

thereof, the same function would be performed as that set forth in the description of the arrangement as figured. Other plans might be adopted, but I propose the one first described.

I wish it to be particularly observed that the cloth or feed in my machine moves along the surface of the table from left to right, as shown by the arrow 40 in Fig. 2.

By this arrangement I increase the assurance that the loop of the needle will be drawn into the notch formed by the hooks, and thus be more certainly caught by them.

I wish also to refer to another highly-important feature in my machine, which, if not new, is certainly not found in others now in most common use by the public. What I refer to is, that while the cloth or feed continues to move always in the above direction, the driving-wheel and main shaft that operate the machinery for producing the stitching may move or revolve in either direction, and hence the operator need have no apprehension of giving a wrong direction to the fly or driving wheel at any time, as it produces precisely the same stitch whatever may be the direction of its revolution or the nature of the stitch to be produced.

The clutches of the feed-wheels may be made to operate in ratchets upon the wheels or cylinders *d* and *e*, Fig. 3.

Having thus fully described the improvements I have made in sewing-machines, what I claim therein as new, and desire to secure by Letters Patent, is—

1. The elliptical cam 6 and its flange 6", in combination with the main shaft 2 and intermediate gearing, all constructed and operating substantially as herein described.

2. The compound cam 7, combined with the looping-arm 16, and constructed to operate substantially as and for the purpose herein set forth.

3. The double-hooked spreader 10, constructed and operating substantially as described.

4. The slotted lip 20, attached to front face of the double-hooked spreader 10, constructed, arranged, and operating substantially as and for the purpose set forth.

5. The combination, as herein described, of the feed-dog 17, friction-wheel 17', and adjusting-screw 17", with the cam 6 6", for imparting vertical and longitudinal motion to the feed-dog 17.

6. The combination, with the above, of the arms 17", and their adjusting screw or screws, and the cam 6', for giving lateral, vertical, and forward motion to the cloth or feed, substantially as herein set forth.

7. The curved letter 16, having its long arm forked or divided, and supported on and made adjustable by the fulcrum-screw 15, substantially as herein described.

8. The needle-bar *C*, when provided with arm *b* for carrying the rods *f* and *g'*, and working in the tube *a*, attached to the front face of

the stationary arm or goose-neck *B*, all substantially in the manner and for the purpose herein set forth.

9. The conical-headed screw, Fig. 7, in combination with the needle-bar *C*, when used to secure the needle in place, substantially as described.

10. The outer cylinder *d'* of the feed-wheel, with its spring *h*, clutch *f*, rod *f'*, and clamp *f''*, when combined, constructed, and operating substantially as set forth.

11. The inner cylinder *e* of the upper feed-wheel, with its corrugated ends, Fig. 6, adjusting-screws *i i'*, and clutch *g*, rods *g'*, clamp *g''*, and spring *h'*, combined, constructed, and operating as set forth, to give lateral motion to the feed-wheel.

12. The combination of the outer feeding cylinder *d* and its appendages with the inner cylinder *e* and its appendages, for giving lateral and forward or retrograde motion to the cloth, as described.

13. The roller, Fig. 8, when used in combination with the upper feed apparatus, in the manner and for the purpose set forth.

14. The adjustable plate, Fig. 9, constructed as described and for the purpose set forth, in combination with the upper and lower feeding apparatus, operating as and for the purpose herein set forth.

15. The looper-needle 31, eyed and pointed at one end, and forked at the other, substantially as described.

16. The combination, with the looper-needle 31, of the notched plate 27, spring 28, pin 29, and screw 30, for fastening and operating the looper-needle, in the manner and for the purpose set forth.

17. The combination of the frame 33 and its arms 33' and 33", with the large wheel 34, and small wheel 35, for winding the thread on the bobbin 23 automatically, substantially as described.

18. The tension-spring 38, in combination with the described winding apparatus for regulating the tension of the thread in its passage from the spool to the bobbin, as described.

19. In sewing-machines, where rotary hooks or spreaders are used to carry a loop around a spool or bobbin, or the spool or bobbin case, the combination of the rotary spreading-hook 10 with a feeding mechanism, feeding the cloth or fabric toward the free face of the hook or spreader, and in a plane at right angles, or nearly so, to the plane of revolution of the said hook or spreader, to cause the loop just forming to be caught with certainty by the point of the hook or spreader.

20. The combination, in a sewing-machine, of two feeding devices, substantially as herein described, when one of them is constructed to feed the material in an opposite direction to the other.

21. The combination, with a sewing-machine, of two feeding devices, constructed substantially as herein described, either one of whi-

may be made to perform alone all the requirements of a feed apparatus, both for zigzag and direct stitches.

22. The combination, with a sewing-machine, of two feeding devices, either of which may be made to perform, substantially as herein described, all the requirements of a feed apparatus for a direct stitch, while the other vibrates or oscillates laterally.

23. The combination, with a sewing-machine, of two feeding devices, constructed and operating substantially as herein described, so that both may have a vibrating, oscillating, or zig-zag motion, in like or opposite directions at the same time, while the stitching continues in a uniform or direct line, thus forming two connected lines of stitches.

24. The combination, with a sewing-machine, of a cylindrical or spheroidal bobbin, a turning or revolving looper-hook, and a forked or

barbed looper vibrating below the bed-plate, when constructed substantially as herein described, so that it will be unnecessary to remove either of these elements or devices therefrom to render the machine capable of making either a single-loop or a back stitch.

25. The combination, in a sewing-machine, of mechanical devices, constructed and arranged substantially as herein described, so as to operate efficiently in making not only a stitch or stitches with three threads, but also in making a stitch or stitches with either one or two threads at option, without the removal therefrom or the addition thereto of any mechanical device or part of the machine used in making a stitch with three threads.

S. P. SLEPPY.
